TOP RAIL

Allwyn E. Symington, Woodside, N. Y.

Application June 8, 1939, Serial No. 278,067

12 Claims. (Cl. 72—115)

The invention relates to a metal reinforced partition and specifically relates to a means for connecting a top rail with a stud or other upright element of the metal reinforcement of the partition.

The present disclosure constitutes a companion application with the disclosure in my copending application Serial No. 278,068 filed under even date and entitled "Method of and means for constructing partitions."

The primary object of the invention is to provide a simplified form of metal reinforcement at the top of a partition, in which the uprights may be quickly and conveniently anchored in position without necessity of using fastening means and to this extent the present disclosure illustrates two structures by means of which the method disclosed in the copending application may be practiced.

The invention particularly features the assembling of the upright to the top rail in such manner that the uprights can be simply hooked in position and then dropped into their finally seated position while being guided by their sliding engagement with the top flange during this seating operation.

The invention has for its general object the providing of a rugged and mutually braced form of metal reinforcing structure which can be constructed of the least possible amount of material and without necessity of using skilled labor in fabricating the structure.

Various other objects and advantages of the invention will be in part obvious from an inspection of the accompanying drawing and in part will be more fully set forth in the following particular description of one form of top rail embodying the invention, and the invention also consists in certain new and novel features of construction and combination of parts herein-after set forth and claimed.

In the accompanying drawing:

Fig. 1 is a plan view of a top rail with its midportion broken away to save space and showing installed in position one of the uprights of the metal reinforcement;

Fig. 2 is a transverse sectional view of the completed partition and adjacent portion of the ceiling with the metal parts taken on the line 2—2 of Fig. 1 looking in the direction indicated by the arrow;

Fig. 3 is a horizontal sectional view looking upwardly on to the top rail from the plane indicated by the line 3—3 of Fig. 1 showing one of the uprights in position in full lines, and another

upright in an intermediate position in dotted outlines;

Figs. 4, 5 and 6 are correspondingly similar views of a modified form of top rail disclosing a different means for anchoring the uprights thereto; and

Figs. 7 and 8 are views respectively similar to Figs. 4 and 5 showing still another modified form of the anchoring means.

10 Referring generally to all of the figures, there is disclosed a ceiling A depending from which is a partition B provided with metal reinforcements C and which include primarily a top rail 10 and a plurality of uprights 11 spaced along the 15 length of the partition B as is usual in such structures.

Referring first to the form of the invention disclosed in Figs. 1 to 3, it will be noted that the top rail includes a relatively short horizontally 20 extending ceiling engaging flange 12 which is secured to the ceiling A by nails 13. This top rail includes a deep, rugged, depending flange 14 which also functions as a guide for the upper end of the uprights. The flange 14 is provided 25 with a plurality of horizontally spaced apart anchors 15 prelocated to define the position of the several uprights 11 which are to be used in the completed partition. As these anchors are similarly formed, the description of one will be 30 sufficient for any of the others. Midheight of the flange 14, it is cut therethrough with two parallel slits 16 and 17 and a connecting slit 18. The portion of metal between these slits is bent 35 at right angles to the plane of the flange to form the anchors as J-shaped socket or tongue open at top and bottom. More specifically described, the anchor comprises a vertically extending plate-like wing 20 which projects integrally at right angles from the flange and is dimensioned 40 to have the web 21 of the upright 11 fit against the same when one of the side flanges 22 of the upright is in sidewise flat abutting engagement with the adjacent side of the flange 14 as shown in Fig. 3. The extension beyond the wing 20 is 45 bent at right angles thereto, engage the other side flange 23 of the upright and is then again bent back upon itself to form an end wing 24 parallel to the wing 20 and designed to receive the upright therebetween. Between the edge of 50 the wing 24 and the adjacent side of the flange 14, there is provided a long opening 25 of sufficient width to permit the upright to be hooked into the same as indicated by the dotted showing to the left of Fig. 3. It is noted that the upper end 26 of the upright 11 is spaced below

flange 12 a distance to permit the lower end of the upright to clear a base rail not herein shown but disclosed in the copending application.

In assembling the parts shown in Figs. 1 to 3, and assuming that the top rail is properly located, the uprights, one after the other, are simply hooked into the tongue or socket and rotated from the dotted line position shown at the left of Fig. 3 into the full line position shown at the right of Fig. 3 after which the upright is permitted to drop down in the direction of its own length, during which time the upper end of the upright is guided in its sliding movement through the tongue and is guided by its engagement with the flange 14.

Referring to the modified form of attachment, shown in Figs. 4 to 6, the depending flange is cut therethrough with two sets of slits. The midportion of the flange is slit along the line 27-28-29 and the portion of metal therebetween is bent at right angles to the plane of the depending flange to form a wing 29' having a width to fit between the side flanges of the upright as shown in Fig. 6. The lower portion of the depending flange 14 is slit along the line 30-31 and the portion of metal between the same and the lower edge 32 of the flange is bent at right angles to its plane to form another wing 33 extending parallel to the wing 29 and disposed on the outer side of the web of the upright. The openings 34 and 35 remaining in the plane of the depending flange are open to each other across the edge 32 to provide a recess for receiving the upper end of the upright.

In assembling the upright into this structure, it is simply pushed upwardly through the recess and extends through the lower opening 35 and partially into the upper opening 34 as shown in Fig. 4. It will be understood that by this construction, the upright is held from all movements except the desired limited movement in the direction of its own length.

Referring to the form of the invention disclosed in Figs. 7 and 8, the lower edge 32 is slit upwardly along four parallel lines including two relatively short lines 36 and 37 and at middistance therebetween along two closely positioned long lines 38 and 39. The lines 38 and 39 are spaced apart a distance slightly greater than the thickness of the web portion of the upright 11. The portion of metal between the long lines 38 and 39 is blanked out to form the slits 36 and 37 on one side of the slot 40 and that between the slits 36 and 37 on the other side are bent out of the plane of the flange 14 to form two horizontally extending ears or plates 41 and 42 each having a width as shown in Fig. 8 to fit between the side flanges of the upright irrespective as to which direction the channel may be facing. Bending the ears out of the flange leaves a recess 43 in the lower edge 32 of the depending plate.

In this form of construction the upright is simply pushed upwardly locating its web in the slot 40 and causing the ears to engage, one fitting in the channel and engaging the channel side of the web with the other engaging the opposite or rear side of the web. In this way the upright is held from rotary movement about its own axis as well as from all other possible movement except the longitudinal movement necessary to locate it in position.

Insofar as all forms of this invention are concerned, the upper ends of the uprights can be easily and quickly inserted in their prefixed definitely located position and locked in position restrained from all undesired movement and this

can be obtained without necessity of welding or otherwise fastening the uprights to the top rail. With the metal reinforcement completely assembled in position, a wall of cementitious material is applied following conventional practices in this respect to complete the partition. It is noted that in both forms of the invention openings such as 34 and 35 in Fig. 4 and openings 36 in Fig. 3 are provided midheight of the depending flange 10 of the top rail and this permits the locking together of the material on opposite sides of the depending flange in the vicinity of the upper ends of the several uprights.

While there have been shown, described and 15 pointed out in the annexed claims, certain novel features of the invention, it will be understood that various omissions, substitutions and changes in the form and details of the device illustrated and in its operation may be made by those skilled 20 in the art without departing from the spirit of the invention.

I claim:

1. A partition including a top rail having a horizontal ceiling engaging flange and a depending flange, a channel shaped upright depending from the rail with its upper end spaced below the ceiling flange, said depending flange being slit and the slit portion bent to extend at right angles to the plane of the depending flange to form a vertically extending wing for engaging one side of the upright and to form an opening in the depending flange, and a wall of cementitious material in which the depending flange and the upright is embedded, with the material extending 30 through the opening and thus tending to lock together the material on opposite sides of the depending flange in the vicinity of the upper end of the upright.

2. A metal reinforcement for a partition including a vertically disposed plate, a channel form of upright having one of its side flanges abutting one side of the plate and having its web extending perpendicular to the plane of the plate, said plate provided with a slit portion 45 forming means integral with the plate and bent from the plane of the plate forming a pair of vertically extending parallel wings extending perpendicular to the plane of the plate, located on opposite sides of the upright and coacting with the plate to locate the adjacent end of the upright in place, and said upright having a limited degree of vertical movement in the direction of its own length, through said means while being guided in such movement by said means 50 and by the plate.

3. A metal reinforcement for a partition including a top rail having a vertically disposed plate, a channel form of upright having one of its side flanges in flatwise abutting relation to the plate for a portion of the vertical width of the plate and having its web extending perpendicular to the plane of the plate, said plate provided with an extension projecting integrally from one side thereof and forming a vertically disposed plate-like wing engaging one face of the web of the channel and having its free end bent back upon itself to form a hook-like end engaging at least one other face of the channel.

4. A partition comprising a horizontally extending L-shaped plate including a horizontally extending ceiling engaging flange and a depending flange, means formed integral with the depending flange, projecting therefrom beneath the ceiling flange bent back upon itself and thus forming a hook-like socket open at top and bot-

tom, a vertically extending element having its upper portion in engagement with and lapping the vertical flange, fitted in the socket, and having its upper end spaced below the ceiling flange.

5. A partition construction comprising a top rail including a vertically extending plate, a channel forming an upright with the upper end of one of its flanges engaging one side of the plate and with its web extending perpendicularly to the plane of the plate, and an anchoring hook having one end secured to the plate and partly surrounding the upright, the end of the hook secured to the plate extending perpendicular thereto and engaging the web of the upright, the opening of the hook being sufficient to permit the upright to be intruded by a rotary movement about a self-contained longitudinal axis into the hook to cause the web of the upright to fit against a portion of the hook fashioned to receive the same.

6. A metallic frame for a partition construction comprising a top rail including a vertically disposed plate, a plurality of uprights engaging at their upper ends one face of the plate, a plurality of hook-like tongues, one for each upright spaced along and secured to the plate and each tongue provided with an opening leading into the interior thereof, partly encircling its associated upright engaging the same along three faces and acting to secure its upright to the plate by virtue of its configuration and otherwise free of fastening means.

7. A metallic partition including a depending flange of a top rail, said flange provided with two sets of slits, the parts outlined by each of said sets of slits being bent in the same direction out of the plane of the flange to form a pair of vertically disposed parallel integral extensions fashioned to secure between them an upright element of the metallic frame.

8. A metallic frame for a partition including a depending flange of a top rail, the lower edge of said flange having a vertically extending slit, an upright having its upper end intruded into the slit, a portion of the flange at one end of the slit being bent out of the plane of the flange to form an extension engaging one side of the upright and a portion of the flange at the other end of the slit also bent out of the plane of the flange to form another lateral extension engaging an opposite side of the upright.

9. A metal reinforcement for a partition including a top rail provided with a ceiling engag-

ing flange having means for securing it to a ceiling and with a depending flange, said flange being slit adjacent its midheight and the part between the slits bent to form a laterally extending wing adapted to engage one side of another element of the reinforcement, the portion of the flange between the first mentioned slits and the lower edge of the depending flange being also slit and the part between these other slits bent to form a wing extending parallel to the first named wing and adapted to engage the opposite side of said other element, and said slits also coacting to form a recess opening from the bottom edge of the depending flange and designed to receive said other element.

10. In a device of the class described, the combination of a top rail including a depending plate provided with a recess in its bottom edge and a slot extending vertically upward from the recess, a channel form of upright having its web intruded into the slot, said upright extending lengthwise downwardly beyond the lower edge of said depending plate in the direction of the plane thereof, said plate provided with two horizontally extending ears bent out of the plane of the plate thus forming the recess and forming plates, one fitting in the channel of the upright and engaging the channel side of the web and the other engaging the opposite side of the channel web.

11. A metal reinforcement for a partition including a top rail provided with a ceiling engaging flange having means for securing it to a ceiling and with a depending flange, said flange provided with a vertically extending slot and also slit inwardly from said lower edge on opposite sides of the slot, the material between the slot and these slits being bent out of the plane of the flange to form a pair of horizontally extending ears adapted to engage opposite sides of a channel form of upright when its upper end is intruded lengthwise past said lower edge into the slot.

12. In combination, a vertically disposed plate, a channel shaped upright extending across the lower edge of the plate, and retaining means integral with the plate and bent therefrom outwardly from the plane of the plate for engaging opposite sides of the upright and acting to resist relative movement between the plate and upright in two directions and engaging at least one side of the web portion of the channel.
